MEANS FOR STEERING SUBMARINE AND SUBMERGIBLE BOATS.

APPLICATION FILED MAY 26, 1904.

2 SHEETS - SHEET 2.

UNITED STATES PATENT OFFICE.

LAWRENCE Y. SPEAR, OF GREENPORT, NEW YORK, ASSIGNOR TO
ELECTRIC BOAT COMPANY, OF GREENPORT, NEW YORK.

MEANS FOR STEERING SUBMARINE AND SUBMERGIBLE BOATS.

No. 812,906.

Specification of Letters Patent.

Patented Feb. 13, 1906.

Application filed May 26, 1904. Serial No. 209,978.

To all whom it may concern:

Be it known that I, LAWRENCE Y. SPEAR, a citizen of the United States, residing at Greenport, in the county of Suffolk and State of New York, have invented certain new and useful Improvements in Means for Steering Submarine and Submergible Boats, of which the following is a specification.

This invention relates to the class of submarine boats wherein the boat is fitted with a compass for maintaining routes when submerged and also with optical instruments or devices known as "altiscopes," "periscopes," &c., which are designed to enable the steersman or observer in the vessel to observe surrounding objects from a point considerably below the level of the water.

The object of the present invention is to improve the construction, mounting, and operativeness of the steering means, as will be hereinafter explained. The novel features of the invention will be carefully defined in the claims.

In the accompanying drawings, which illustrate an embodiment of the invention, Figure 1 is a sectional elevation taken along the longitudinal axis of the boat, showing the devices mainly in elevation and the boat and conning-tower in vertical section; and Fig. 2 is a view of the same parts or devices as seen from the left in Fig. 1. Figs. 3, 4, 5, and 6 are enlarged fragmentary detail views. In these views Fig. 3 is a sectional view showing the gearing for driving the indicator. Fig. 4 is a horizontal section, as at line 4⁴ in Fig. 1. Fig. 5 is an enlarged view of the lower part of the optical tube and the eyepiece, and Fig. 6 is an enlarged view showing the construction of the indicator in detail.

40 B designates a fragment of the hull of the boat, and T a part of the conning-tower, turret, or sighting-hood mounted thereon.

1 is the main steering-wheel, coupled by gears 2 with a shaft 3, from which the rudder is operated by any suitable connective gearing. This wheel is designed to be operated by a helmsman or steersman. 5 is an auxiliary steering-wheel for the observer or commander, from which the shaft 3 may also be driven through a chain 6 and sprocket-wheels 7.

At the side of the tower T and preferably disposed in the plane passing through the boat's longitudinal axis forward is an up-

right socket or sheath 8 to receive an optical tube 9. (Seen in axial longitudinal section in Fig. 1.) The socket 8 may be cast or made in one piece with the tower, as shown; but this integral construction is not essential to the present invention. The optical tube is fitted or supplied in any desired manner with reflectors and, if desired, with lenses, in order to receive an image at its upper exterior end and deflect the same from its lower interior end into a substantially horizontal plane, where it may be observed through an eyepiece 10 from the interior of the conning-tower. The tube 9 is fitted removably in its socket and mounted rotatably about its vertical axis, and it has the necessary means for preventing access of water to the outer end of the socket and to enable it to rotate axially without undue friction. The means for effecting these ends (illustrated in Fig. 1) are substantially the same as those shown in my United States Patent No. 751,569, and are not herein claimed.

In the present construction the reflector at the upper and outer end of the optical tube is a prism 11, inclosed in a box or casing 12, borne on the upper end of the tube. This prism turns with the tube, so as to face in any direction desired. The lower reflector, however, which is a prism 13, is not carried by nor rotative with the tube 9, but is set or fitted in a fixed casting or hollow support 14, (seen in section in Fig. 1,) which has on its upper face a short cylindrical tube 15, that fits accurately into the lower end of the optical tube and forms a bearing to support and center the lower end of the tube 9 and connect it operatively with the eyepiece 10 and lower prism 13. The socket 16 of the eyepiece is screwed or otherwise secured in the inner upright face of the casting 14 and has a water-tight connection with the, upright front plate 17 of a chamber C, which incloses the lower prism 13 and the adjacent parts. The inner end of the eyepiece socket that is to say, the end within the chamber C is closed water-tight by a transparent plate 18. (Seen in Fig. 5.) The tube of the eyepiece may be telescopically slidable in the socket 16.

On the optical tube 9 within the chamber C is secured a gear-wheel 19, which gears with a toothed wheel 20, fixed on the upper part of an upright shaft 21, which passes down

through the bottom plate 17* of the chamber C and is rotatable in a stuffing-box 22 therein. The shaft 21 may be rotated by any known means, as a crank or hand-wheel 21* thereon. It is not material to this invention how this shaft is rotated. It is only necessary to explain that through the medium of this shaft and the gears the optical tube may be turned about its upright axis, while the lower prism or reflector 13 remains stationary with respect to the tube 9.

In order that the observer may note the bearing of the object of which he sees the image through the eyepiece, the following means are employed:

Within the chamber C is a pinion 23, gearing with the wheel 19 and serving to transmit motion through shafts 24 and 25 and gear-wheels 26, Fig. 3, to the hand or pointer 4 of an indicator on the front plate of the chamber C. This indicator comprises a disk 27 with a sleeve-like stem in which the shaft 25, bearing the pointer, rotates. This disk is stationary, and in its face is mounted rotatively but frictionally a compass-card 28. This card may be turned about over the face of the disk, but will be held by suitable frictional means in any position desired. (See Fig. 6.) On this card is a lubber's line or mark *a*, which when the instrument has its optical tube so turned that the upper reflector or prism 11 receives an image of an object which is directly ahead will be coincident with the pointer 4 of the indicator, and in the optical tube is a cross-wire *w*, which under the same circumstances will be coincident with a vertical plane passing through the longitudinal axis of the boat. This wire divides the field of view into two equal parts. Below the chamber C is a telltale-compass 29 within the view of the eye *e* of the observer at the eyepiece, and below this compass is mounted a suitable magnifying-lens 30 and a frictionally-hinged reflector 31. The eye *e'* of the steersman will be so situated as to command the image in the reflector 31.

The tight receptacle or chamber C is connected by a pipe 32 with a holder 33 of dry air and by a pipe 34 with a vacuum-pump 35. In the pipe 32 is a stop-valve *v* and in the pipe 33 a stop-valve *v'*. To prevent moisture in the air in the chamber C and the optical tube from condensing on and fogging the faces of the glasses or reflectors, the air may be pumped from the said chamber and tube by the pump 35. The pump may then be cut off by the stop-valve *v'* and the valve *v* opened to admit artificially-dried air to the said parts. The casting or support 14 in the chamber C will have in it one or more apertures 36 to admit dry air to the prism 13 and to the optical tube, and a receptacle, as 37, for a deliquescent salt may be placed in the chamber C to assist in drying the air.

It may be stated here that the base of the

upper prism 11 closes the upper end of the optical tube 9 air-tight, so that when the air is removed from the instrument by the pump or other air-exhausting means a nearly perfect vacuum may be formed into which the dried air rushes from the holder 33. This invention is not concerned with any special means for drying the air, as it is not new to dry air and force it through the optical tube of an altiscope provided with a pressure-valve at its upper end. This construction and disposition of parts is intended to provide a station for the commanding officer or navigator, hereinbefore called the "observer," and for an independent steersman or helmsman. With this arrangement the commanding officer may perform the following functions without changing his position: First, (a) command the vessel when on the surface, awash, or submerged, either through the usual sighting-ports of the conning-tower or by compass or, by means of the optical tube; (b) search the horizon by means of the optical tube and take compass-bearings with the combined dummy compass and indicator-gear, at the same time keeping check upon the compass-courses steered by the independent steersman stationed at the lower steering-wheel; second, take charge of the actual steering of the vessel when he so desires while conning through the sighting-ports by compass or through the optical tube.

The present invention relates to the means for steering the vessel or boat, as set forth definitely in the claims. The other specific features shown herein form the subject-matter of copending divisions of this application, Serial Nos. 238,796 and 238,797. These last-named features, which relate to the optical tube and means for preventing condensation of moisture therein, are illustrated and described herein because of their close relation to the present invention and because they are constructively combined with the steering devices in actual practice.

What I claim as my invention is—

1. A submarine boat, having an upright socket to receive the optical tube of an altiscope or like instrument, the said tube, open at its lower end and carrying at its upper end a deflecting-reflector to receive the image, a chamber within the boat below said socket, a hollow support 14 in said chamber, said support having a neck 15 which enters the lower end of the optical tube, a deflecting-reflector 13 in said support, an eyepiece-socket 16 extending through the wall of the said chamber and connected with said wall and with the support 14, the glass 18 in the inner end of the socket 16, the eyepiece mounted slidably in said socket 16, means for rotating the optical tube, a visual indicator actuated by the rotation of said tube to indicate the extent of its rotation, and a telltale-compass 29 situated adjacent to the said eyepiece.

130

2. A submarine boat, having an optical instrument for receiving and deflecting an image down to the eyepiece of the instrument within the boat for observation, means for 5 rotating axially the optical tube of said instrument, a visual indicator operated by said tube and adjacent to the said eyepiece, to denote the degree of rotation of the tube, a telltale-compass below and adjacent to the eyepiece, a magnifying-lens below said compass, and a reflector below said lens to reflect the 10 readings of the compass to the steersman below.

3. A submarine boat having a steering-wheel and mechanism for a steersman, or 15 helmsman, an auxiliary steering-wheel above

the level of the latter for the observer, connecting mechanism whereby the boat may be steered by said auxiliary wheel, a telltale-compass within the range of vision of the observer, and a magnifying-lens and reflector, the latter being so disposed as to reflect the 20 readings of said compass within the range of vision of the steersman below.

In witness whereof I have hereunto signed 25 my name, this 23d day of May, 1904, in the presence of two subscribing witnesses.

LAWRENCE Y. SPEAR.
